UNITED STATES PATENT OFFICE.

ROY J. CANTRELL, OF SAN FRANCISCO, CALIFORNIA.

CLOTHES-LINE HOLDER.

933,620.

Specification of Letters Patent. Patented Sept. 7, 1909.

Application filed March 16, 1909. Serial No. 483,713.

To all whom it may concern:

Be it known that I, ROY J. CANTRELL, citizen of the United States, residing in the city and county of San Francisco and State of California, have invented new and useful Improvements in Clothes-Line Holders, of which the following is a specification.

My invention relates to a clothes-line and holder or case for the same.

10 Its object is to provide a simple, cheap, practical, neat-appearing, adjustable clothes-line holder for use in the kitchen or other room in a house, or for use in a yard where space is limited and it is not always convenient or desirable to have a stationary clothes-line hung at all times.

20 The invention consists of the parts and the construction and combination of parts as hereinafter more fully described and 25 claimed, having reference to the accompanying drawings, in which—

Figure 1 is a front view showing the cover removed. Fig. 2 is a side elevation partly in section. Fig. 3 is a section on line X—X, 25 Fig. 1. Fig. 4 is a perspective view of the clamp member.

30 In the embodiment of the invention as actually practiced, and suitable for two lines each fifteen to twenty feet in length, I employ a casing, as A, having a removable cover 2, which houses the lines 3 and weights 4, and which casing is approximately five feet in length, one inch in thickness, and an inch and a half in width, and adapted to be 35 installed as a permanent part of a room, or to be secured permanently to any suitable support by any appropriate means. Manifestly, though, these dimensions may vary, according to the size, length and number of 40 lines used. Also, while in practice I make the casing out of a molding strip of special design, it is manifest that it may be made of any suitable material and appropriate shape.

45 Preferably, for a two-line holder the casing is made with two lengthwise extending grooves 5 separated by a lengthwise extending slot 6 in the casing. A weight 4 slides in each groove or slide-way 5, and each line 50 3 is suitably rove around a respective pulley 7 on a weight and a fixed double sheave 8 at the top of the casing; the free end of each cord preferably having a ring 9 by which the cord may be grasped and pulled 55 forth from the casing and engaged with a hook 10 or other suitable support across the

room when it is desired to use the line. The slot 6 is important because it provides a means of adjustment for the stops 11, by which the limit of upward movement of each 60 weight is determined, and by which the adjustment of each line for any particular room or space is effected, as will be described shortly. Each of these stops 11 comprises a strip of sheet-metal bent up at one 65 end to form a flange 12, and adapted to bridge the slot, and with a downwardly turned guide flange 13 projecting into one of the grooves 5; a set-screw and thumb-nut 14 serving to lock the stop at any suitable 70 place. The screw has a head 15 which fits an enlarged countersunk groove 16 in the back of the casing, so as to permit the stop to be adjusted up and down after the casing has been secured with its back against the 75 wall in permanent position, by suitable means, as the screws 17. With two lines and weights to a casing, as here shown, one of the stops 11 projects to one side of the slot 6, and the other to the other side, so that 80 neither stop will interfere with the proper working of the other line, but will allow independent adjustment of either line.

85 The cover 2 is preferably made detachable, and may be secured in any suitable fashion to the casing. As here shown, the cover is a little shorter than the casing, and the latter has two cap-shaped members 18—19 respectively at top and bottom of the casing forming a seat for the beveled ends of the 90 cover. The space between the opposed front flanges of the caps 19—18 is a little less than the length of the cover 2, so that the latter, which consists of a flexible wooden strip, can be easily put in place by simply 95 inserting one end of the strip in the lower cap, and then bending the strip so that the other end can pass up into the top cap; the strip straightening as soon as allowed to, and closing the casing; the function of the 100 cover being to form a front guide for the weights, and preventing their being displaced from their regular slide-ways 5. If desired, suitable locking means 20 are employed to hold the cover in place. Also, the 105 top edge of the cover is provided with a notch 21 for each line, out through which notches the lines are passed; the lines being prevented from falling back into the casing when the weights strike their lowest 110 point, by the engagement of the rings 9 with the cover.

In practice, the frame or holder is screwed to the wall, or casing of a door, or other suitable support, by means of the screws 17, this being done before the cover is put on. 5 The lines or cords 3 being suitably connected to the weights and rove around the pulleys 7-8, are received into the notches 21, and the cover put in position, after regulating the stop 11 according to the length of line required. 10 By taking hold of the ring attached to the exposed end of the cord, the cord is drawn forth from the casing, thereby raising the weight, and a suitable length of cord is drawn forth, according to the space available in which the line is temporarily 15 to be suspended. The ring is then hooked over a nail or hook, as 10. Since, however, each weight only weighs a few ounces, and it is only designed to act automatically to 20 retract the cord into the casing when released from its connection 10, it is manifest that some means must be provided to limit the further upward movement of the weight when a particular line has been adjusted to 25 the particular space available. Consequently, the reasons become apparent for the adjustable stops 11; and each stop is adjusted so as to intercept its respective weight when the proper length of line has been drawn 30 forth sufficient to engage its hook 10 and maintain the line taut. By means of the stop 11 the weight is prevented from rising, so that clothes may be hung on the line without the latter sagging. When once set by 35 means of the adjustable devices 11 the line is always ready for use, so that only the desired amount of line sufficient to engage its hook 10 and maintain the line tight and secure under all conditions, can be drawn out 40 of the casing. If a longer line is needed, or a new point of attachment 10 for the line is found, or the device is to be set up in another room or location, requiring a different length of line, then the stop 11 is adjusted accordingly. 45 With the line vacant, the line is automatically rewound within the casing by means of the weight, on detaching the ring from the hook on the wall.

It is manifest that the number of lines and 50 weights housed within a single casing may be varied at will, but in any case a single

slot 6 in the casing will provide means for the attachment of two stops 11.

Having thus described my invention, what I claim and desire to secure by Letters Patent is—

1. The combination in a clothes-line holder, of a vertical casing, a weight housed and slideable in the casing, a pulley in the top of the casing and a pulley on the weight, 60 a line connected to the weight and rove around the pulleys and passing outside the casing, and means shiftable on the casing and acting on the weight for limiting the amount of line to be withdrawn from the 65 casing.

2. The combination in a clothes-line holder, of a casing having a plurality of vertical guide grooves, the casing having a slot between the grooves, adjustable stops 70 secured in said slot, weights sliding in the grooves and interceptable by said stops, pulleys arranged at the top of the casing, and lines connected to respective of said weights and passing around respective of said pulleys, said lines operative to be withdrawn from the casing, and rewound therein, by 75 means of the weights.

3. The combination in a clothes-line holder, of a casing having a plurality of vertical guide grooves, the casing having a slot between the grooves, adjustable stops secured in said slot, weights sliding in the grooves and interceptable by said stops, pulleys arranged at the top of the casing, 80 lines connected to respective of said weights and passing around respective of said pulleys, said lines operative to be withdrawn from the casing, and rewound therein, by means of the weights, and a cover for said 85 casing, said casing having opposed top and bottom caps spaced apart a distance less than the length of the cover, and said cover of springy material and adapted to be sprung within said caps and held therein. 90

In testimony whereof I have hereunto set my hand in presence of two subscribing witnesses.

ROY J. CANTRELL.
